UNITED STATES PATENT OFFICE.

KRIKOR ATAMIAN, OF ST. LOUIS, MISSOURI, ASSIGNOR OF ONE-HALF TO LAURA M. SCARBOROUGH, OF ST. LOUIS, MISSOURI.

FIRE-ESCAPE.

1,333,530.

Specification of Letters Patent.

Patented Mar. 9, 1920.

Application filed April 12, 1919. Serial No. 289,561.

To all whom it may concern:

Be it known that I, KRIKOR ATAMIAN, a citizen of the United States, residing at St. Louis, State of Missouri, have invented new and useful Improvements in Fire-Escapes, of which the following is a specification.

This invention relates to fire escapes and has for its object the provision of a device of this character which is simple of construction and efficient in operation and which may be placed adjacent a window or other opening and readily moved to a position for use.

Another object of the invention is the provision of a fire escape employing a rope or cable, which is unwound from a drum by the person descending, the speed of such unwinding being automatically governed so as not to be affected by the person's weight; thus a heavy person would descend at the same speed as a child.

Another object is the provision of a device of the above character in which the rope or cable is automatically rewound when relieved by the weight of the person, so as to be again in position for use.

A further object is the provision of a fire escape having an alarm device, which will be automatically operated by the operation of the escape, thereby directing attention of persons to the fire or giving notification of the unauthorized use of the device.

Other objects and advantages of the invention will appear as the following description is read in connection with the accompanying drawings.

In the drawings:

Figure 1 is an elevation of a window showing the position of the fire escape when not in use.

Fig. 2 is a sectional view through the window showing the fire escape in position for use.

Fig. 3 is an enlarged sectional view through the device *per se*.

Fig. 4 is a section on the line 4—4 of Fig. 3.

Fig. 5 is a similar view on the line 5—5, and

Fig. 6 is a like view on the line 6—6.

Referring in detail to the drawings, wherein like characters of reference denote corresponding parts, the device is shown as positioned adjacent a window casing, indi-

cated at 10. To accomplish this there is provided a bracket 11, having pivotally secured thereto through the medium of a pin 12, an arm 13, the latter supporting at its outer end a fire escape about to be described. While the device is illustrated as permanently mounted upon the arm 13, so as to be swung into and out of the window, it is, of course, obvious that it may be of a portable nature, with suitable means provided for detachable engagement with a window opening or the cornice or roof of a building.

The fire escape comprises a casing of preferably cylindrical form, as shown at 14, within which is secured heads 15 and 16, both of these heads being provided with inwardly extending annular flanges 17, which are secured to the casing 14. The head 16 is slightly spaced from the adjacent end of the cylindrical casing, this last mentioned end being provided with a closure 18, so that a separate compartment is provided for an alarm mechanism to be later described.

Mounted within the bearings formed in the heads 15 and 16, is a shaft 19 and secured to this shaft is a hollow drum 20, carrying at opposite ends flanges or heads 21 and 22, the latter being detachably secured through the medium of screws or similar fastening devices 23. A wire cable or rope 24 has one end secured to the drum 20, and is adapted to be wound thereon between the flanges 21 and 22, the said cable or rope operating through an opening 25 in the casing 14 and having secured to its extremity a stirrup 26, which is adapted to receive the foot of the person using the fire escape.

When in use, the weight of the descending person will unwind the rope or cable, causing the drum 20 to revolve, and for the purpose of regulating the speed of this drum and consequently the speed of descent, there is provided an automatically operated brake. This brake comprises a pair of substantially semi-circular brake shoes 27, which are pivotally secured together upon a pin 28, the latter being carried by the flange 22 of the drum, causing the shoes to revolve with the drum. Operating between the opposite or free ends of the shoes 27, is a cam or spreader 29, the latter being pivotally mounted upon the flange 22 and having pivotally secured thereto one end of an arm 30. The opposite end of this arm is bifurcated

or slotted for the reception of a pin 31, which is eccentrically mounted upon a disk 32, rotatable upon the shaft 19.

Pivots mounted in the flange or head 22, as indicated at 33 and extending within the drum 20, are levers 34, the short arms of the said levers extending outward from the said flange or head and each having pivotally connected thereto one end of a rod 35. The opposite ends of these rods are pivotally connected upon diametrically opposite sides of the shaft 10, to the disk 32, so that an inward movement of the short arms of the levers 34, will rotate the disk 32, and through the medium of the rod 30 operate the cam or spreader 29 to spread the shoes 27 into contacting engagement with the inner periphery of the flange 17 of the head 15, this flange being preferably provided with a suitable friction lining 36. The shoes are normally held from engagement with the flange through the medium of a spring 37, while a spring 38 secured to the long arms of the levers 34 serves to normally retract the levers or to counter-act the centrifugal force due to the operation of the drum.

Surrounding the shaft 19 between the head 16 and the adjacent head of the drum 20, is a coiled spring 39, one end of this spring being secured to the flange of the head 16, as shown at 40 and the opposite end being secured to the shaft 19, as indicated at 41, the head 16 and its flange forming a housing for the said spring, which is closed by the adjacent head or drum 20. This serves to maintain the spring in proper alignment and will minimize the danger of breakage due to twisting or buckling of the spring. The shaft 19 extends through the head 16 and has secured thereon a toothed wheel 42, which is adapted to engage a roller 43, mounted upon one end of a pawl 44. This pawl is pivotally secured to the head 16 upon a pin 45 and carries at its opposite end a spring arm 46. The free end of the arm 46 has secured thereon a hammer or tappet 47, which is designed to operate between lugs 48 extending inwardly from a gong 49.

It will be thus apparent that when the shaft is revolved by either the unwinding or winding of the rope or cable, the dog 44 will be moved upon its pivot and the spring arm 46 vibrated, so as to contact with the lugs 48 to sound the gong. The roller 43 is held in contact with the teeth of the wheel 42 through the action of a spring 50.

From the foregoing description and the accompanying drawings it will be seen that the weight of a person descending will unwind the rope or cable, causing the drum 20 to revolve, its speed of operation being controlled through the action of the centrifugal levers 34, which operate the brake shoes 27 and cause them to engage the inner periphery of the flange 17 of the head 15, the de-

gree of such engagement being governed by the weight of the person using the escape. As the rope or cable is unwound, the spring 39 will be wound and when the said rope or cable is relieved of its weight, the spring 70 will be sufficiently tensioned to rewind the rope or cable so as to bring the stirrup into position for further use.

It will be further apparent that the alarm will be sounded during both the unwinding and winding of the rope or cable, thereby directing the attention of a person to the fire or causing alarm to be sounded should the fire escape be used by an unauthorized person, such as a burglar.

The invention is susceptible of various changes in its form, proportions and minor details of construction and the right is herein reserved to make such changes as properly fall within the scope of the appended 85 claims.

Having described the invention, what is claimed is:

1. A fire escape embodying a casing, means for supporting the same, a shaft mounted to 90 revolve within the casing, a hollow drum secured upon said shaft, a cable adapted to be wound upon the drum, a centrifugal governor operating within the hollow drum, a brake shoe engageable with the casing and means including an eccentrically mounted pin rotatable about the shaft and operated by the governor to operate the brake shoe and control the speed of the drum.

2. A fire escape embodying a casing, means for supporting the same, a shaft mounted to 100 revolve within the casing, a hollow drum secured upon said shaft, a cable adapted to be wound upon the drum, levers pivotally mounted within the drum and disposed longitudinally of the shaft, a disk mounted to revolve upon the shaft, rods connecting one end of the levers with the disk for imparting a rotary movement to the latter and a brake shoe engageable with the casing and connected to the disk for controlling the speed of the drum.

3. A fire escape embodying a casing, a shaft rotatably mounted therein, a hollow drum secured upon said shaft, a cable wound upon 115 the drum, pivotally mounted centrifugally operated levers disposed longitudinally of the shaft, a disk mounted to revolve upon said shaft, means connecting the levers and disk, brake shoes pivotally mounted upon 120 the drum for contact with the casing, a cam pivotally mounted upon the drum between the brake shoes and adapted to be operated to force the latter into contact with the casing and means connecting the cam and disk, 125 whereby centrifugal action of the levers will rotate the disk and operate the cam.

4. A fire escape embodying a casing, a shaft rotatably mounted therein, a hollow drum secured upon said shaft, a cable wound upon 130

the drum, pivotally mounted centrifugally operated levers disposed longitudinally of the shaft, a disk mounted to revolve upon said shaft, means connecting the levers and disk, brake shoes pivotally mounted upon the drum for contact with the casing, a cam pivotally mounted upon the drum between the brake shoes and adapted to be operated

to force the latter into contact with the casing, an arm pivotally connected to the cam 10 and an eccentric pin carried by the disk and engageable with the arm, whereby centrifugal action of the levers will rotate the disk and operate the cam.

In testimony whereof I affix my signature.
KRIKOR ATAMIAN.
